ELECTRIC CONTROL PANELBOARD

William Robertson and Louis W. Higgins, Detroit,
Mich., assignors to BullDog Electric Products
Company, Detroit, Mich., a corporation of West
Virginia

Application March 22, 1949, Serial No. 1,560

Term of patent 14 years

(Cl. D26—5)

To all whom it may concern:

Be it known that we, William Robertson and Louis W. Higgins, citizens of the United States and residents of Detroit, Michigan, have invented a certain new, original, and ornamental Design for an Electric Control Panelboard, of which the following is a specification, reference being had therein to the accompanying drawings.

In these drawings:

Fig. 1 is a front elevational view of an electric control panelboard with a front door closed, showing our new design.

Fig. 2 is a side elevational view as if looking from the right of Fig. 1.

Fig. 3 is a fragmentary view, generally similar to Fig. 1, but showing the panelboard with the front door open.

Fig. 4 is a top plan view of the panelboard, as if looking down on Fig. 1.

We claim:

The ornamental design for an electric control panelboard, substantially as shown.

WILLIAM ROBERTSON.

LOUIS W. HIGGINS.
